BLOUSE OR THE LIKE

Phillip Selznick, Los Angeles, Calif., assignor to Leon P. Goldstein, Los Angeles, Calif.

Application August 12, 1949, Serial No. 4,442

Term of patent 3½ years

(C1. D3—25)

To all whom it may concern:

Be it known that I, Phillip Selznick, a citizen of the United States, residing at Los Angeles, in the county of Los Angeles, State of California, have invented a new, original, and ornamental Design for a Blouse or the like, of which the following is a specification, reference being had to the accompanying drawing forming a part thereof.

I claim:

The ornamental design for a blouse or the like, substantially as shown and described.

PHILLIP SELZNICK.
